Patented Apr. 29, 1919.

UNITED STATES PATENT OFFICE.

ELMER S. TANQUARY, OF LAWRENCEVILLE, ILLINOIS.

FRETTING DEVICE FOR MUSICAL INSTRUMENTS.

1,302,451.

Specification of Letters Patent. Patented Apr. 29, 1919.

Application filed August 6, 1917. Serial No. 184,700.

To all whom it may concern:

Be it known that I, ELMER S. TANQUARY, a citizen of the United States, residing at Lawrenceville, in the county of Lawrence 5 and State of Illinois, have invented certain new and useful Improvements in Fretting Devices for Musical Instruments; and I do hereby declare the following to be a full, clear, and exact description of the invention, 10 such as will enable others skilled in the art to which it appertains to make and use the same.

This invention relates to string instruments of the type in which the player picks 15 or strikes the strings by the finger or a picking device held in the hand.

The present invention has relation especially to the playing of Hawaiian music on the guitar, during which process the player 20 holds in the left hand a steel and in the right hand holds a picker which is moved across the strings in connection with the movement of the steel along the neck of the guitar to produce the various chords or notes. Obviously this system of playing the guitar is imperfect for the reason that the player cannot 25 properly fret the strings of the instrument to produce true chords, and the present invention has for its object the production of 30 true chords by the player of the instrument in playing Hawaiian music.

With the above and other objects in view, a feature of the invention consists of means for fingering the strings of the instrument 35 when it is moved relative to a convenient support independent of the instrument; the fingering means being attached to the instrument and to the support by articulated and flexible means.

Obviously, such a device might be utilized 40 in the playing of various string instruments and in the following specification and in the accompanying drawings, it has been disclosed in association with a guitar for the 45 purposes of illustration only.

The invention consists of the construction, the parts and the combination of parts and details of arrangement as will be more fully described hereinafter and shown in the accompanying drawings, in which one form of 50 the invention is illustrated, and in which drawing,

Figure 1 is a perspective view of the instrument and the device applied thereto;

Fig. 2 is a side elevation of the device as 55 applied to the neck of a guitar on an enlarged scale to show the parts in detail;

Fig. 3 is a plan view of the fingering device; and

Fig. 4 is a diagrammatic view illustrating 60 a portion of the neck of a guitar and designating the strings as tuned for the playing of Hawaiian music.

Fig. 5 is a cross-section on line 5—5 of 65 Fig. 2.

In the drawing a guitar is shown as having the usual strings S of which the first three are tuned to give C, A and F, respectively, one change in the tonic chord A, for instance, being produced by the simultaneous 70 contact or depression of the "A" string at the first fret and the "C" string at the second fret; another being produced by the simultaneous depression of the "A" string at the first fret and the "F" string at the second 75 fret; another by the simultaneous depression of the "F"—"A"—"C" strings at the second fret, and a fourth and minor being secured by depressing "C" string at the second fret while "A" and "F" are left open. To produce these various changes while playing 80 guitar music in Hawaiian style, I have devised a fingering or stop member or block 4 which preferably is relatively thick and may be made of any material though steel is preferred. The block 4 is approximately 85 triangular in plan view and is provided at its narrow end with an abutting ridge 5 and at its wider end with abutting ridge 6 spaced in such relation to each other that when the 90 block 4 is mounted in suitable position upon the neck of a guitar the fretting ridge 5 is adapted to stand over or adjacent the first fret 2 and the ridge 6 is adapted to stand adjacent the second fret designated 3 so that 95 upon movement of the block 4 with relation to the strings C, A and F the various desired chords may be produced. The block 4 may be conveniently and readily attached to the neck of the guitar by any simple and suitable 100 means as a clamp here shown as comprising a plate 7 having a band or other suitable or resilient clamping portion 8 which may be passed around the lower portion of the neck of the guitar so as to removably but firmly 105 hold the plate 7 in position between the first and second frets of the guitar neck. The plate 7 is provided with an upwardly pro-

jecting neck or stem 9 preferably articulately connected to the block 4 by a ball and socket joint 10, permitting fingering movement of the block to selectively engage the given strings at predetermined positions.

To control and secure the proper relative fingering movement of the block 4 during the playing of the instrument, the block is connected by any suitable means to a relatively stationary structure shown here as a support or stand 12 which the player may position conveniently with relation to the neck of the instrument, the stand 12 having an arm 13 which may be suitably adjusted upon the stand 12 and which is provided at its outer end with a connector, 14 preferably of rubber, designed to be readily connected to the block 4. The connector 14 which provides for articulation is provided in this instance with a socket 15 to receive the upwardly projecting stem 16 formed on or suitably secured to the top of the block 4.

When the clamp plate 7 has been arranged upon the neck of the guitar between the first and second frets as shown in Fig. 2, the block is then held with its ridge portions 5 and 6 respectively over the strings and adjacent to the first and second frets and the portion 5 stands above the string A while the portion 6 extends above, and crosses the strings C, F and A at the second fret. The spacing of the points of the fretting ridges 5 and 6 above the strings may be readily adjusted by any simple and suitable means shown for instance as comprising a screw 17 which may form a portion of the ball and socket joint 10, the screw being threaded in the block or block 4 so that adjustment of it will cause the latter to be lifted or lowered relatively to the strings.

During the playing of the instrument, the operation is substantially as follows. The guitar is placed across the knees of the player, the stand 12 arranged at the neck 45 of the instrument in a suitable position, and the socket or connector 14 is coupled into the connected portion 16 of the block 4 after the latter has been previously connected to the neck of the guitar by the adjustment of the 50 clamp or plate 7 thereon. With the strings turned as before mentioned and all of them in the open position, the passage of the picker across the first three strings produces a major triad or tonic chord in the key of F. 55 To produce a change in this chord by fretting the string A at the first fret and the string C at the second fret, the operator simply has to gently laterally swing or sway the neck of the guitar relative to the stand 60 12 so as to cause the fretting ridges 5 and 6 to respectively engage and depress the string A at the first fret and the string C at the second fret, thus leaving the string F open. To produce another change in this 65 tonic chord, the string A may be depressed

at the first fret and the string F at the second fret by a relative lateral change in the position of the guitar neck as to the stand 12 so as to cause the block 4 to so change its position that the fretting portion 5 and the 70 fretting portion 6 respectively engage the string A at the first fret and the string F at the second fret; to produce another change in the chord, the operator simply has to move the guitar longitudinally forward as to 75 cause the rear fretting edge 6 of the stop block to simultaneously engage and depress the strings F, A and C at the second fret; to produce a relative minor it is only necessary for the operator to slightly sway the 80 guitar neck so that the fretting ridge 6 of the block will depress the string C at the second fret, leaving all of the remaining strings open.

From the foregoing it will be seen that I 85 have provided a very simple, practicable, inexpensive and readily operated means for variously fretting the strings of the instrument to produce the different chords which may be required in the playing of music as 90 above mentioned. Moreover, the device is of such nature that it may be connected to a guitar or other instrument to be played without in any way injuring the surface or requiring any alterations to the instrument. 95

Manifestly various changes in the details of construction, the arrangement of the parts and their sizes and proportions may be readily resorted to within the principle of the present invention and the appended 100 claims.

While the device has been shown as applied to the instrument for the playing of the tonic chord in F and related chords on the first and second frets of the instrument, 105 of course the device will operate with equal facility in other positions on the strings and may be designed so as to produce various other chords which may be desired according to the nature of the instrument to be 110 fretted and the relative differences in the strings.

What is claimed as new is:—

1. A device for fingering or stopping strings of a musical instrument, comprising 115 a support independent of the instrument, a stopping block having flexible connection with the support and engageable with the strings, and articulated means for connecting the said block to the instrument, whereby upon relative movement of the instrument and the support the block engages the strings at desired positions.

2. A device for fingering or stopping strings of a musical instrument, comprising 125 a support independent of the instrument, a stopping block having flexible connection with the support and engageable with the strings, and articulated means for connecting the said block to the instrument, where- 130

by upon relative movement of the instrument and the support the block engages the strings at desired positions.

3. A device for fretting or stopping 5 strings of a musical instrument, comprising a support independent of the instrument, a stopping block attached to the said support, and a clamp connected by a universal joint to said block and adapted for attachment to 10 the instrument, whereby when the device is applied, upon the movement of the instrument relative to said element, the stopping block is tilted to stop desired strings at given frets or positions.

15 4. A device for fretting or stopping strings of a musical instrument, comprising a support independent of the instrument, a stopping block movably attached to the said support, and a clamp connected by a 20 universal joint to said block and adapted for attachment to the instrument, whereby, when the device is applied, upon the movement of the instrument relative to said element, the stopping block is tilted to 25 stop desired strings at given frets or positions.

5. In combination with a stringed musical instrument; a fretting block, a clamp upon which it is mounted for universal rocking 30 movement and which is detachably connected to the instrument, and means independ-

ent of the instrument, connected to the block so that upon relative movement of said means and instrument the block is rocked to selectively engage the strings.

35

6. A device for fretting a stringed musical instrument, comprising a stand, an arm adjustable thereon and having a socket member, a fretting block detachably connected to the socket member, and a clamp on which 40 the block is pivoted and which is attachable to the neck of the instrument.

7. A device for fretting or fingering a 45 stringed musical instrument, comprising a fretting block, means for connecting the block to the instrument for universal pivotal movement above the strings, a stand, and means for connecting the stand and said block, whereby upon movement of the instrument relative to the stand, the block is 50 rocked.

8. A device for fretting or fingering a 55 stringed musical instrument, comprising a fretting block, means on which the block is mounted for universal pivotal movement, and adapted for clamping engagement with the instrument, and means for bodily adjusting the block toward or from the clamping means.

In testimony whereof I affix my signature. 60

ELMER S. TANQUARY.
